(57) **CLAIM**

The ornamental design for an adsorbed vase, as shown and described.

DESCRIPTION

FIG. 1 is a top view of an adsorbed vase showing my new design;

FIG. 2 is a bottom view thereof;

FIG. 3 is a front view thereof;

FIG. 4 is a rear view thereof;

FIG. 5 is a left side elevational view thereof;

FIG. 6 is a right side elevational view thereof; and,

FIG. 7 is a top perspective view 1 thereof.

The broken lines shown in the figures represent portions of the adsorbed vase that form no part of the claimed design.
